UNITED STATES PATENT OFFICE.

MORRIS FULLER BENTON, OF PLAINFIELD, NEW JERSEY, ASSIGNOR TO AMERICAN
TYPE FOUNDERS COMPANY, OF JERSEY CITY, NEW JERSEY, A CORPORATION
OF NEW JERSEY.

DESIGN FOR A FONT OF TYPE.

46,721.

Specification for Design.

Patented Dec. 8, 1914.

Application filed October 6, 1913. Serial No. 793,766. Term of patent 14 years.

To all whom it may concern:

Be it known that I, MORRIS F. BENTON, a citizen of the United States, residing at Plainfield, Union county, and State of New Jersey, have invented a new, original, and ornamental Design for a Font of Type, of which the following is a specification.

The accompanying drawing which is made a part hereof and to which reference is made, shows the face and form of each letter and character composing said font of type, as well as the ornamental character of the font as a whole.

Copies of this patent may be obtained for five cents each, by addressing the "Commissioner of Patents, Washington, D. C."

What I claim is:

The ornamental design for a font of type shown in the accompanying drawing.

In witness whereof, I have hereunto set my hand and seal at Jersey City, New Jersey, this eighth day of September, A. D. nineteen hundred and thirteen.
